UNITED STATES PATENT OFFICE.

CARL ALRIK HULT AND OSCAR WALFRID HULT, OF STOCKHOLM, SWEDEN.

SUSPENSION DEVICE FOR OUTBOARD MOTORS.

1,118,011.

Specification of Letters Patent. Patented Nov. 24, 1914.

Application filed July 3, 1913. Serial No. 777,153.

To all whom it may concern:

Be it known that we, CARL ALRIK HULT and OSCAR WALFRID HULT, subjects of the King of Sweden, and residents of 1 Ingelsgatan, Stockholm, in the Kingdom of Sweden, engineers, have invented certain new and useful Improvements in Suspension Devices for Outboard Motors, of which the following is a specification, references being made to the accompanying drawings.

The present invention relates to outboard motor suspension devices of the type in which the motor may turn in bows, sleeves, or the like, surrounding the motor cylinder or cylinders, or a part or parts connected with the motor cylinder, or the motor cylinders.

The invention, which is specially intended for larger outboard motors, comprises such an arrangement of the said suspension devices that the motor itself can be readily removed from the suspension device (which latter remains fixed to the boat) and parts carried by the device, such as the propeller and parts belonging to it or descending to it, and that the whole can be mounted on the boat with greater ease, and be more conveniently accommodated in it, when dismounted.

The invention is characterized mainly by the fact that a part, *e. g.* a frame, a support, or the like, including a sleeve (or sleeves) or the like surrounding the motor shaft, and which part is adjustable relatively to the clamp by means of which the suspension device is securely fixed to the boat, is guided by the clamping members engaging the motor cylinders and the parts placed in the said clamping members in such a manner that the motor shaft or its bearing can be inserted into the sleeve (or sleeves) no matter what position the frame etc. occupies relatively to the clamp (or corresponding part).

In the accompanying drawings is shown by way of example a suspension device carried out in accordance with this invention.

Figures 1 and 2 show the suspension device with a motor placed in it, seen from in front and from one end respectively, while Fig. 3 shows a section taken along the line A--B in Fig. 1 (the motor cylinder is not shown in section). Fig. 4 shows a longitudinal section of a sleeve and parts in it.

The invention is shown applied, by way of example, to a so-called balance motor, *i. e.* a motor with two cylinders situated so as to oppose each other. The cylinders 1 are surrounded by clamping bows 2. These clamping bows 2 are carried by arms 3, extending from a clamp 4, which is fixed to the boat with the aid of bow-shaped parts and clamping screws 5 placed in them. An outer sleeve 6, which surrounds the motor shaft 1^a forms the central part of a frame consisting of arms 7 extending obliquely upward from the lower end of the sleeve, and arms 8, projecting horizontally from the upper end of the sleeve. The arms 7 and 8 join and are prolonged by arms 9 extending obliquely upward and outward. The lower parts of the clamping bows 2, from which parts the arms 3 descend, are not in immediate contact with the cylinders 1, but between them and the cylinders there are arched spaces 10, in which the correspondingly formed free ends 9^a of the arms 9 are jammed whereby the motor is firmly kept in the said bows. The breadth of the ends 9^a is so adjusted that the ends can occupy different positions in the spaces 10, *i. e.* that the frame 7, 8, 9 can be adjusted to different angles relatively to the clamp 4. Moreover, the arrangement is such that the center line of the frame sleeve 6 cuts the center line common to the two clamping bows. The consequence of this is that the motor shaft 1^a, or the bearing 11 surrounding it, can always be inserted downward in the frame sleeve 6 with any usual shape of stern, *i. e.* no matter what the relative position of the frame 7, 8, and 9 and the clamping piece 4 may be. When the motor shaft 1^a is inserted in the frame sleeve 6, it becomes, with the aid of a coupling device in the said sleeve, coupled together with a shaft 12, which forms an extension of said motor shaft, and which shaft is with the aid of a gearing coupled to the propeller shaft.

The coupling device in question, which must admit of the shaft 12 being raised and lowered in order to adjust the propeller to the desired height, may suitably be constructed in the following manner. The frame sleeve 6 surrounds a sleeve 14 (the so-called "conveying sleeve"), which at each of its ends is provided with an inwardly directed wedge 15 and 16 respectively. (Instead of two edges, there may

obviously be only one, extending from the upper end of the conveying sleeve to its lower end). The upper wedge 15 enters a groove 17, arranged in the motor shaft, 6 while the lower wedge 16 enters a groove 18 arranged in the prolongation shaft 12. Between the frame sleeve 6 and the conveying sleeve 14 there is a sleeve 19, which surrounds and is firmly connected with the 10 bearing 20 of the shaft 12, which bearing extends upward from the casing 21 containing the gearing between the shaft 12 and the propeller shaft. The conveying sleeve 14 is firmly connected with the motor shaft 1* 15 with the aid of a screw 14*. The frame sleeve 6 is slotted at its lower end and has a screw 22 for clamping the said end around the intermediate sleeve 19. When the screw 22 has been loosened, the intermediate sleeve 20 19 and the parts connected with it, as well as the propeller, can be raised or lowered in a vertical direction (and also turned, if required), the wedge groove 18 then being moved relatively to the wedge 16. When 25 the propeller has thus been adjusted to the desired height (it is shown in Fig. 1 in its highest position), the lower end of the frame sleeve is again tightened around the intermediate sleeve 19. The steering of the 30 boat is effected, according to the drawings, by turning a sleeve 23 surrounding the intermediate sleeve 19 and on which sleeve 23 the rudder is fixed.

Having now described our invention, 35 what we claim as new and desire to secure by Letters Patent is:

1. In a device of the character described, the combination of a boat, a motor therefor having an extended motor shaft, a clamp

attachable to said boat and having clamping means for holding said motor, and a motor support including a sleeve embracing said motor shaft, said support having parts adapted to be clamped by said clamping means between them and the motor. 40

2. In a device of the character described, the combination of a boat, a motor therefor having opposed cylinders and an extended motor shaft, a clamp attachable to said boat and having clamping means for embracing the cylinders of the motor, and a motor support including a sleeve embracing the motor shaft, said support having projecting arms adapted to enter between the clamping means and the motor cylinders whereby said 50 support is suspended in adjustable position.

3. In a device of the character described, the combination of a boat, a motor therefor having opposed cylinders and an extended motor shaft, a clamp attachable to said boat 60 and having a pair of oppositely arranged substantially annular clamping means adapted to encircle the said cylinders, there being a space between each cylinder and the clamping means encircling the same, and a substantially triangular frame embodying a central sleeve embracing the motor shaft and short, laterally projecting, arms adapted to be held in the space between the said 65 cylinders and the said clamping means. 70

In witness whereof we hereunto set our hands in presence of two witnesses.

CARL ALRIK HULT.
OSCAR WALFRID HULT.
